UNITED STATES PATENT OFFICE

2,024,247

BLASTING CARTRIDGE

Charles B. Officer, Chicago, Ill., assignor to Safety
Mining Company, Chicago, Ill., a corporation of
Illinois

Application June 1, 1933, Serial No. 673,883

10 Claims. (Cl. 102—6)

This invention relates to means for blasting, and more particularly, but not exclusively, to improvements in blasting cartridges of the pressure fluid ruptured type especially adapted to use in the "air shooting" of coal or similar materials.

In the "air shooting" of coal, by means of cartridges containing suddenly released charges of highly compressed air, carbon dioxide, or the like, it is best to cause release of the charge in a direction such that the reaction will tend to press the cartridge towards the back of the coal, as otherwise it might become a projectile capable of serious damage. As the coal falls, however, the pressure supply line or the like is dragged by the falling coal in an outward direction, and it is therefore desirable to effect a disconnection between the line and the cartridge.

An object of this invention is to provide an improved means for breaking down coal. A further object is to provide an improved blasting cartridge wherein the rupturing force is derived from means other than explosives. Another object is to provide an improved blasting cartridge of the pressure fluid ruptured type wherein the cartridge is burst by a relatively high pressure within the cartridge. A further object is to provide a blasting cartridge having parts separable upon a predetermined blasting pressure within the cartridge and having means for causing an increase in and for effecting release of the pressure within the cartridge and including an element having connections with one of the separable portions of the cartridge, so that when the blast or release of pressure occurs, the said element is released from the cartridge casing. A still further object is to provide in a cartridge of the pressure fluid "exploded" type an improved releasable fluid connection for connecting the pipe line to the cartridge casing. Still another object is to provide an improved blasting cartridge of the type wherein a rupturable end wall is employed for releasing the blasting pressure and having improved means for connecting the pipe line to the rupturable end wall whereby upon rupture of the end wall the connection is released from the cartridge casing. These and other objects and advantages of this invention will, however, hereinafter more fully appear.

In the accompanying drawing there is shown for purposes of illustration one form and a modification thereof which the invention may assume in practice.

In this drawing,—

Fig. 1 is a diagrammatic view illustrating the association of the blasting cartridge with a wall of material to be blasted.

Fig. 2 is a longitudinal section showing the illustrative form of the improved cartridge, a portion of the cartridge casing being shown in side elevation.

Fig. 3 is a detail view of the rupturable disc of the cartridge of Fig. 2.

Fig. 4 is a fragmentary view similar to Fig. 2 showing a modified form of construction.

In this illustrative embodiment of the invention, Fig. 1 shows a wall of coal 1 or similar material to be blasted having an undercut 2 and a drill hole 3 into which is inserted a blasting cartridge generally designated 4 of an improved design. This cartridge has connected thereto a pipe line 10 5 which is in turn connected to the receiver tank 6 of a high pressure compressor 7 mounted on a wheeled truck 8 adapted to run along a mine trackway 9 laid on the floor of the mine chamber 10. The drill hole at the outer end of the cartridge is tamped at 11, and the pipe line 5 extends outwardly from the drill hole through this tamping in the manner shown. Fluid under pressure is supplied from the compressor receiver tank through the pipe line 5 to the cartridge, and upon a predetermined blasting pressure built up within the cartridge the latter bursts whereupon the pressure will be released from the cartridge casing and expanded in the wall of the material to be broken thereby to force down the material 15 from the mine wall.

Now referring to the improved cartridge, it will be observed that the same comprises a cylindrical shell or tubing 12 having an integral end closure or end wall 13 at its inner end. The 30 outer end of the casing is closed by a rupturable end wall, herein a metal disc or plate 14 of less strength than the walls of the casing 12. This rupturable disc or plate 14 is seated at its periphery against an annular shoulder or flange 15 35 formed integral with the casing 12, and the disc or plate is held tightly in its seated position against the shoulder to form a fluid tight joint by a sleeve-like plug 16 threaded at 17 within the cartridge casing. The pipe line 5 in the preferred 40 form of the invention is threadedly connected at 18, as shown in Fig. 2, within a nipple 19 in turn threadedly connected at 20 within a boss 21 formed integral with the rupturable disc 14. In the modification shown in Fig. 4, the pipe line 45 5 is threadedly connected at 22 directly within the boss 21 of the rupturable disc, the nipple in this form of the invention being omitted.

In this improved construction, when the desired rupturable pressure is reached within the 50 cartridge casing, the disc 14 is ruptured, thereby releasing the blasting pressure from the casing. Upon the rupturing of the disc 14, the pipe line 15, which is connected to the disc, is released from the cartridge casing, thereby diminishing 55 the possibility of injury of the pipe line, due to falling of the blasted material thereon or sudden movement of the cartridge casing relative thereto, so that when it is again desired to use the cartridge for another blasting operation, the 60

same pipe line is simply connected to a new disc. In the ordinary rupture of frangible closure discs it has been found that they tend to bulge, and then shear adjacent their peripheries, there being little tendency to transverse rupture. Accordingly, it will be evident that the pipe connection will be exposed to little likelihood of injury and may be used repeatedly with new discs.

It is not desired to limit the invention to the particular cartridge construction shown, it being obvious that instead of connecting the pipe line to the rupturable disc, the pipe line may be connected to an element which does not rupture upon release of the blasting pressure, for instance a portion of the cartridge casing which merely releases or separates from the body of the cartridge when the blast is effected. It will also be noted that the invention may be practiced with blasting cartridges of types other than that disclosed herein, for instance a blasting cartridge of the carbon-dioxide or other gaseous types wherein an electric igniter or heater is employed to cause an increase in the pressure or explosion within the cartridge, it being evident that the invention described herein may be practiced by connecting the wires leading to the igniter or heater to a separable or rupturable portion of the cartridge casing so that when the blast occurs and the parts separate or rupture, the wires will be released from the cartridge casing. In other words, it will be evident that the invention may be practiced with various types of blasting cartridges wherein it is desired to effect release from the cartridge casing of the means which effects the explosion or the increase in the blasting pressure.

As a result of this invention it will be noted that an improved blasting cartridge is provided wherein the means for effecting the blasting operation or the increase in the blasting pressure is released from the cartridge casing when the blast occurs, thereby to prevent injury thereto by the falling of the blasted material or the sudden movement of the cartridge casing relative thereto due to the "explosion". It will further be noted that an improved blasting cartridge of the pressure fluid "exploded" type is provided wherein the pipe line for supplying the blasting pressure to the cartridge is automatically released from the cartridge casing upon bursting of the cartridge. It will further be noted that an improved blasting cartridge is provided, which is of an extremely simple design and may be manufactured at a minimum of expense, it being necessary only to replace a relatively inexpensive part after each blasting operation. These and other uses and advantages of the improved blasting cartridge will be clearly apparent to those skilled in the art.

While there is in this application specifically described one form and certain modifications thereof which the invention may assume in practice, it will be understood that this form and the modifications are disclosed for purposes of illustration and that the invention may be modified and embodied in various other forms without departing from its spirit or the scope of the appended claims.

What I claim as new and desire to secure by Letters Patent is:

1. In a blasting cartridge, a casing having a separable portion, and means for effecting release of the blasting pressure within the cartridge upon separation of said portion and

including a blast effecting element having a blast effecting connection solely with said separable portion, said portion upon separation thereof releasing automatically said connection from said casing.

2. In a blasting cartridge, a casing having a rupturable portion, and means for supplying a blasting pressure within said casing including a pressure conducting member having a connection with the rupturable portion of said casing.

3. In a blasting cartridge, a casing having a rupturable end wall, and means for supplying a rupturable pressure to the cartridge casing having a connection solely with said rupturable end wall, said end wall upon rupture thereof releasing automatically said pressure connection from said casing.

4. In a blasting cartridge, a cartridge casing, a rupturable disc closing one end of said casing, and means for supplying a rupturable pressure to the casing having a connection in said disc, said disc upon rupture thereof releasing automatically said supply connection from said casing.

5. In a blasting cartridge, a casing having a rupturable end wall, and a pipe line for supplying a rupturable pressure to the casing having a connection with said end wall.

6. In a blasting cartridge, a cartridge casing, a rupturable disc for closing one end of said casing, and a pipe line for supplying a rupturable pressure to the casing having a connection with said disc.

7. In a blasting cartridge, a casing having all its walls of a strength to support a predetermined minimum desired pressure and one of its walls weaker than the remainder to localize rupture when a predetermined higher pressure is attained, and means for effecting the attainment of such higher pressure including a pressure effecting connection solely with said weaker wall, said weaker wall upon rupture thereof releasing automatically said connection from said casing.

8. In a blasting cartridge, a casing having a rupturable portion adapted to break when a predetermined blasting pressure is attained within said casing, and means for effecting the attainment of such blasting pressure including a pressure effecting connection solely with said rupturable portion, said portion upon rupture thereof releasing automatically said pressure connection from said casing.

9. In a blasting cartridge, a casing having a rupturable end wall adapted to break when a predetermined blasting pressure is attained within said casing, and means for effecting the attainment of such blasting pressure including a pressure effecting connection solely with said rupturable end wall, said end wall upon rupture thereof releasing automatically said pressure connection from said casing.

10. In a blasting cartridge, a cartridge casing, a rupturable disc closing one end of said casing and adapted to break when a predetermined blasting pressure is attained within said casing, and means for effecting the attainment of such blasting pressure including a pressure effecting connection solely with said rupturable disc, said disc upon rupture thereof releasing automatically said pressure connection from said casing.
